IGNITION CONTROL APPARATUS

Kenneth R. Blake, Detroit, Mich.

Application May 14, 1937, Serial No. 142,645

1 Claim. (Cl. 123—148)

This invention relates to control means for variably loaded electrical circuits, as for instance the electrical system of an automobile which supplies current to the spark plugs for ignition purposes and which also operate the starter, the lights and other equipment, and has for its object to provide an automatic means which will guard a predetermined portion of said circuits, as for instance, the ignition system, against a drop in potential below the requirements thereof as are likely to be occasioned by simultaneous use of other portions of the circuit such as the starting circuit.

When an automobile is at rest and it is desired to start the engine, operation of the starter consumes a very substantial percentage of the possible power output of the battery causing a severe drop in potential at the gaps of the spark plugs. During this period of starting the spark plug potential should be at a maximum for easy starting. Also, when the engine is turning at a very high rate of speed the distributor points are opening and closing with such rapidity that the contact resistance substantially lowers the voltage effective on the ignition coil and thereby decreases the potential at the spark plug gaps. In addition, when rapid acceleration is called for by the automobile operator it is advantageous to provide a spark of increased intensity. It is, therefore, an object of the invention to provide means for automatically controlling the circuits in order to prove the optimum electrical conditions for automobile operation.

The electrical circuit of an automobile includes a battery, a line from the battery to a primary coil with the manual switch and a resistor in the line, a line from the primary to the arms of the distributor, a secondary coil, and a line leading from the secondary to the shaft of the distributor. The output of the secondary is dependent upon the induced current from the primary and hence if the resistor is shunted the output of the primary will be materially increased. It is, therefore, an object of this invention to provide means, both electrical and mechanical, which will respond to one or more variations from normal operation to shunt the resistor. As will be more fully described, the variations to which the shunting devices may be responsive are: during engine starting, during acceleration and during abnormally high engine speeds.

A clear understanding of the various modes of altering the circuits will become hereinafter more fully apparent as reference is had to the accom-

panying drawings wherein my invention is illustrated in several forms and in which—

Fig. 1 is a diagram of an engine ignition circuit with my invention incorporated.

Fig. 2 is a detail showing a modification of the arrangement of the resistor of Fig. 1.

Fig. 3 is a modification of the diagram of Fig. 1, the operation of the accelerator pedal being employed as an electrical control means.

Fig. 4 is a horizontal sectional detail of the mechanism of Fig. 3 which directly responds to the accelerator pedal.

Fig. 5 is a modification of Fig. 1 in which the generator acts as the control means.

Fig. 6 is a longitudinal section through the end of the generator to which the control means is attached.

Fig. 7 is a diametric section taken along the line 7—7 of Fig. 6, and

Fig. 8 is a modification of Fig. 5 wherein the coil is modified.

More particularly when the ignition switch 1 is closed current flows from the battery 2 through the lead 3, through a resistor 4, through the lead 5 to the primary 6 of the ignition coil, thence through the line 7 to a terminal 8, thence to the breaker arm 9 of a conventional distributor 10, through the contacts 11, and through the line 12 to a ground 13. A secondary coil 14 grounded at 15 is connected by the line 16 to the distributor shaft 17. To this point the circuit is conventional.

The current flow from the secondary winding 14 is dependent upon the current flow in the primary 6. The flow through the winding 6 can be increased by shunting the resistance 4 as will now be described.

At a point 18, between the ignition switch 1 and the resistor 4, a line 19 of a shunt circuit is connected. This shunt includes the line 19, a terminal 20, a line 21, contacts 22 and a terminal 24 in the line 5. One of the contacts 22 is stationary and the other one is carried by a bi-metallic blade 25 which is positioned in close proximity to the primary winding 6.

In operation, when the engine is cold the contacts 22 are closed so that upon energization of the starter motor (not shown) current to the distributor will flow through the shunt circuit, by-passing the resistor 4. After the engine starts the voltage and, hence, the current flow to the distributor will increase whereupon the winding 6 begins to heat. The bi-metallic arm 25 is set sufficiently close to the primary so that after a short interval of time, which may be predeter-

mined, the contacts 22 will separate and all further current flow must occur through the resistor 4. So long as the effective voltage remains at or above, say, six volts, sufficient heat will be produced in the coil 6 to maintain the contacts 22 separated.

A further shunt circuit is capable of responding to engine acceleration when the contacts 22 are open to cut out the resistance 4. This circuit 10 consists of a line 26 connected to the terminal 20 of the line 19, 21 and to a terminal in the base of a conductive spring arm 27 carrying a contact 28, a contact 29, and a line 30 which connects the contact 29 with the line 5 at 31. The 15 spring arm 27 carries a piece of insulation 32 for contact by a plunger 33 fixedly secured to a piston 34. The piston 34 is movably contacted in a cylinder 35 subject to the changing pressures in the intake manifold of the engine (not shown) 20 by virtue of a line 36. A spring 37 urges the piston 34 outwardly against the direction of suction in the line 36.

During normal engine operation, the piston 34 is urged inwardly against the pressure of the 25 spring 37 by the vacuum in the manifold thus permitting the spring arm 27 to flex and to break contact of the contact points 28 and 29. In the event of rapid acceleration of the engine, the 30 vacuum in the intake manifold, and hence in the line 36, is lost to the extent that the spring 37 urges the piston 34 and the plunger 33 outwardly against the spring arm 27 thus closing the contacts 28 and 29 whereby the shunt circuit is completed and the resistor 4 by-passed.

35 In Fig. 2 the numbers 8a, 18a, 21a, 22a, 23a, 24a and 25a correspond to the numbers 8, 18, 21, 22, 23, 24 and 25 respectively of Fig. 1. In the event that the bi-metallic arm 25a is not sufficiently close to the winding 6 to be responsive thereto, 40 the arm may be enclosed in insulation and a resistor coil 38 wound therearound, this resistor being in parallel with the primary winding 6.

45 In Fig. 3, 39 indicates an accelerator pedal connected by a linkage 40 to an arm 41 of a switch device 42. This device has two terminals 43 and 44. A contact plate 45 having an insulated portion 46 is mounted for rotation by the arm 41. When the accelerator pedal is depressed a sufficient amount to rotate the insulated portion 46 from contact with the terminal 44 the terminals 43 and 44 are then electrically connected. The 50 remainder of the circuit will now be described. A battery 45 has a line 46 leading therefrom to an ignition switch 47, past a terminal 48 through a resistor 49, past a terminal 50, thence to the primary winding 51 of an ignition coil. The circuit is conventional as was described in connection with Fig. 1 so that the complete showing and complete description is omitted. Leading from the terminal 48 is the shunt circuit which consists of a line 52, a terminal 53 a line 54 connecting the terminal 53 with the terminal 43, and a line 55 connecting the terminal 44 to the terminal 50.

55 In operation, when the throttle 39 is sufficiently depressed to establish electrical connection between the terminals 43 and 44 the current flow is from the battery 45 through the lines 52 and 54 to the terminal 43, thence to terminal 44 and to the terminal 50 to the primary 51. The resistor 49 is thus shunted, the shunting occurring at any predetermined point of depression of the accelerator pedal 39 which corresponds, generally, to a pre-determined engine power requirement.

70 In this circuit, a further shunt circuit may be added, identical with the circuit 26, 27, 28, 29, 30,

of Fig. 1. It is the circuit 28a, 29a, 30a, 31a wherein the parts correspond as implied by the addition of the letter "a". The vacuum switch device is indicated by the numerals 36a and 31a.

Figs. 5, 6 and 7 illustrate a circuit in which the resistor is by-passed at a predetermined engine speed. The original circuit is composed of battery 55. The manual switch 56, the resistor 57 and the primary winding 58, the complete circuit being the same as that illustrated in Fig. 1. From 10 a terminal 59 between the switch 56 and the resistor 57 a lead 60 extends through a terminal 61 and is thereafter connected to a coil 62 having a core 63 therein. A line 64 connects the solenoid coil 62 to a terminal 65 of a centrifugal switch 15 66. The switch parts are composed of a grounded shaft 67 which rotates at or proportionate to the speed of the engine and which carries a plate 68. Offset from the center of this plate 68 is a pin 69 upon which is journalled a horseshoe shaped 20 weight 70 having a contact brush 71 mounted near one end thereof. A spring 72 urges the weight 70 in contacting position with a stop 73. As the shaft 67 rotates the weight tends to swing outwardly and to rotate about its journal pin 69 so that when 25 a sufficient speed of rotation is attained the brush 71 will contact the terminal 65 and close the circuit to the ground permitting a flow of current from the battery 55 through the line 60, and through the coil 62 thus affecting energization of 30 the solenoid 62, 63. An armature 74 pivotally mounted adjacent the core 63 will be drawn thereagainst thus closing the contacts 75. Leading from the terminal 61 is a line 76 to one of the contacts 75 and the armature 74 is connected by a 35 line 77 to the primary winding 58 at the terminal 78. It will thus be seen that when the switch 66 is closed, the flow of current may occur from the battery 55 through the line 60, the line 76, contact 75. The armature 74, line 77, and to the primary 40 winding 58 thus by-passing the resistor 57.

45 As a further means of by-passing the resistor 57, a lead 79 may be tapped into the line 60 at the terminal 80 and connected through a vacuum switch 81 similar to the vacuum switch of Fig. 1. 45 previously described, and then connected by a line 82 to the primary winding 58.

50 In Fig. 8, a circuit is shown which is capable of overcoming the tapering off of the ignition potential at high speeds, which is due to unsaturation of the primary coil.

In this case the circuit is as follows:

55 The battery 84 supplies a line 85 having an ignition switch 86 and a resistor 87 therein and which is connected to the primary winding 88. The primary is in two parts, being divided at the terminal 89 where a line 90 leads therefrom to the contacts 91. One of the contacts 91 is fixed and the other is carried by an armature 92 in circuit with a line 93 leading to the terminal 94 of the distributor 95. A line from the top of the total primary coil leads to a terminal 97 in the line 88 and hence to the distributor terminal 94. The armature 92 is subject to a solenoid 62a, 63a, connected into the line 76, in exactly the same 65 manner as was described in connection with Fig. 5 as to the armature 74, the solenoids 62, 63 and the allied parts of the circuit.

70 It will thus be seen that the portions of the primary winding between the terminal 89 and 70 the line 90 increases the total resistance of the circuit to a point greater than the resistance developed by the distributor breaker point at high speeds. This fact assures an output at high speeds sufficient to produce good ignition. That 75

portion of the primary winding between the resistor 87 and the terminal 89 is used during normal operation of speed and/or low voltages during starting. When the engine is running at an average speed current therefor flows through the lower portion of the coil only. When the speed of the engine is increased to the point where the centrifugal switch 66a functions to energize the solenoids 62a, 63a the contacts 91 are broken and current then flows through the upper part of the primary winding, through the line 96 and to the distributor 95. Due to the fact that when the breaker points are operating at high speed they develop a resistance sufficiently high to decrease the average current flowing through the primary. Therefore, in order to keep the output up to normal the resistance must be increased along with the number of turns until the total number of ampere-turns developed are practically the same as when the speed is lower. It will thus be seen that I have provided several ways of altering the resistance of portions of the ignition system in response to variations in speed characteristics of the engine, "speed characteristics" may be defined as including idle

conditions; normal constant operating conditions, the mechanically indicated speed as derived by the position of the throttle, the speed of a rotating engine shaft, the acceleration as defined by manifold vacuum and the like.

Other applications of my invention will occur to those skilled in the art and I, therefore, desire to be extended protection within the scope of the appended claim.

What I claim is:

The combination of an ignition system for an internal combustion engine comprising a source of current supply, the engine ignition circuit including a coil and a resistor between said coil and said source of current supply, a shunt circuit around said resistor having a switch therein, said switch being normally closed when the engine is idle and during periods of engine starting, and means responsive to a predetermined temperature of said coil to open said switch, said last named means being responsive to a coil temperature resulting from a flow of current therethrough of predetermined voltage.

KENNETH R. BLAKE. 25
